HAND POINTER FOR A GAME BOARD OR SIMILAR ARTICLE

Jacob B. Burke, 6771 Yellowstone Blvd., Forest Hills,
N.Y. 11375, and Ziva G. Rosen, 100 W. 57th St.,
New York, N.Y. 10019

Filed Aug. 22, 1973, Ser. No. 390,503

Term of patent 14 years

Int. Cl. D21—01
U.S. Cl. D34—5 MM

FIG. 1 is a top plan view of a hand pointer for a game board or similar article showing our new design.

FIG. 2 is an end elevational view of the hand pointer.

FIG. 3 and FIG. 4 are cross sectional views taken on lines 3—3 and 4—4 respectively of FIG. 1.

FIG. 5 is a bottom plan view of the hand pointer.

FIG. 6 is a top plan view of another embodiment of the hand pointer, wherein certain ridges are replaced by grooves.

FIG. 7 is an end elevational view of the hand pointer of FIG. 6.

FIG. 8 and FIG. 9 are cross sectional views taken on lines 8—8 and 9—9 respectively of FIG. 6.

FIG. 10 is a bottom plan view of the hand pointer of FIG. 6.

We claim:

The ornamental design for a hand pointer for a game board or similar article, as shown and described.
